CLAIM

The ornamental design for a mobile tag device, as shown and described.

DESCRIPTION

FIG. 1 is a front perspective view of the new design for a mobile tag device in accordance with the present invention; FIG. 2 is a rear perspective view thereof;

FIG. 3 is a front elevation view thereof;

FIG. 4 is a rear elevation view thereof;

FIG. 5 is a first side elevation view thereof;

FIG. 6 is a second side elevation view thereof;

FIG. 7 is a top plan view thereof; and,

FIG. 8 is a bottom plan view thereof.

The broken lines illustrate portions of the mobile tag device that form no part of the claimed design.

1 Claim, 8 Drawing Sheets(56)
